BOOK INDICATOR

Rebecca Cohen, Brooklyn, N. Y.

Application April 4, 1938, Serial No. 199,864

1 Claim. (Cl. 116—119)

This invention relates to book indicators whereby a reader will have a positive indication of the page number and the line of the page where the reader has left off while reading the book.

5 An object of this invention is to provide a book indicator having an elongated strip with a fold at one end designed to engage the upper end of a page and having a slot lengthwise thereof for engaging and guiding a numbered indicator up or down the page to the particular line last left off in reading the book.

10 Another object of this invention is to provide in combination with an elongated and slotted strip having means at one end for securing to the top edge of a page, a numbered indicator having a slotted pointer on top thereof, through which slot the reader may see at a glance the page number last left off.

15 Another object of this invention is to provide a numbered indicator which will provide the reader with the information of the month, date and page and also the last line left off for the reader to resume reading.

With the above and other objects in view, the 20 invention will be hereinafter more particularly described, and the combination and arrangement of parts will be shown in the accompanying drawing and pointed out in the claim which forms part of this specification.

25 Reference will now be had to the drawing, wherein like numerals of reference designate corresponding parts throughout the several views, in which:

Figure 1 is a perspective view of a book, showing the application of my book indicator thereto.

Figure 2 is a front elevation of the assembled book indicator showing a set month, day and page number.

Figure 3 is a side elevation of the construction 30 shown in Figure 2.

Figure 4 is a fragmentary view of a modified carrier.

In the illustrated embodiment of the invention, the numeral 10 indicates my book indicator 35 comprising an elongated carrier member 11 of strip form and having a slot 12 centrally thereof and substantially throughout its entire length.

As best shown in Figure 3, one end of the carrier member 11 has been folded at one end. The

40 fold 13 is designed to form a clip for embracing the opposite faces of the upper portion of the pages 14 of a book 15 so that the slot 12 may form a guide track extending downward from the upper end of the book.

45 Rotatably mounted on a pivot 16 are a plu-

rality of circular disks 17, 18, 19, 20. The pivot 16 extends into engagement with the slot 12 and so that the said disks are in slidable relation with said carrier member 11. Pivotally mounted on top of the upper disk 20 is a pointer 5 5 21. It is to be noted that all the disks and the pointer form a slidable unit relative to said carrier.

The pointer 21 has a slot 22 lengthwise thereof. The slot 22 is of sufficient length to permit 10 vision therethrough of the end portions of all the disks.

As best shown in Figure 2, the disks 17 to 20, inclusive, have indicia thereon all around their outer circumferences. A line of indicia 15 comprising all said disks may thus be viewed through the slot 22.

For the purposes of the present invention which is to provide means for indicating at a glance the page last left off by the reader, I prefer to print numbers from 0 to 50 on the disks 17 and 18. On the disk 19 I prefer to print numbers from 1 to 31. On the top disk 20 I prefer to print indicia indicating the months of the year. For this purpose I may also print on the pointer 25 21 indicia indicating the month, day, and page. I may also print on the pointer indicia indicating a particular year inasmuch as this book indicator may be used as a greeting device so that the sender may set the two top disks with 30 indicia indicating the year, the month and the day, that is the birthday of the particular person to whom it may be sent as a greeting device.

From the above it will be noted that the reader 35 of a book may attach the device to the book with the folded portion of clip 13 in engagement with the upper portion of the pages as shown, and by manipulating the disks 17 and 18 may indicate the page number last left off. Also the pointer 21 in the particular setting may 40 be rotated jointly with the said disks to a point where the pointer will be in line with the line last left off. The above relates to the use of the device when placed directly side-by-side with the page last left off, wherein it is possible to 45 indicate the last line itself. It is, however, within the province of this invention to mount the device inside the cover and in that case the reader may set the book indicator to indicate the page number last left off without having 50 recourse to the pointer for indicating the line last left off.

Referring to Figure 2, it will be seen that the disks 20 and 19 having the month and day 55 indicia make it possible for the reader to also

indicate the month and day on which the particular page was last left off for the reader to resume reading.

It is to be noted that the material of which the carrier 11 is made will have an element of rigidity or stiffness so that it will be adapted to maintain its form while the upper members are slid thereon. The device may be made of paper, Celluloid, leather or metal having the necessary body.

10 It is to be noted that the entire device is hidden inside the book when not in use.

15 This book indicator may have advertising matter printed thereon and serve as a greeting device which may be given away as a gift. The device may also serve as a perpetual reminder so that the month and date indications may serve to remind the reader of appointments made.

20 Referring to Figure 4 which shows a modified carrier 25 having an unslotted bottom layer 26 so that a pivot may be slidably mounted in the slot 27 of the top layer 28 without contacting the page of the book. The intact layer 26 is attached in any suitable manner to the top layer 28 and thus serves as a shield to guard the pages of the book against damage by the 25 slideable pivot.

25 I may also modify the clip portion of the carrier by providing a metallic clip 29 secured at one end of the carrier. The clip 29 will serve to 30 positively grip the pages of the book.

It is to be noted that while I have shown my book indicator in Figure 1 with the carrier in contact with the upper margin of the pages of the book, that I may reverse the indicator so that the clip end of the carrier will contact the bottom margin of the pages or that it may contact the side edge of the pages.

I claim:

A book indicator composed of top, intermediate and bottom members, said intermediate member comprising a plurality of concentric disks each having indicia concentrically positioned at the outer circumference thereof, said bottom member forming a carrier for said disks and comprising an elongated strip having means at one end for engaging the opposite faces of a page of the book and being slotted substantially throughout its length, said top member forming a pointer having a slot lengthwise thereof for viewing indicia on said disks and having a sharp angular outer end, said disks and said top and bottom members being centrally secured by pivot means, said top and intermediate members being jointly slideable as a unit relative to said carrier member due to engagement of said pivot means with said slot in said carrier member, said carrier having an intact and unslotted bottom layer for shielding said book from contact with said pivot.

REBECCA COHEN.
